(57) **CLAIM**

The ornamental design for a packaging container, as shown and described.

DESCRIPTION

FIG. 1 is a perspective view of my new design, showing a packaging container;

FIG. 2 is another perspective view thereof, shown in an alternate position;

FIG. 3 is a front elevation view of the packaging container of FIG. 1;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view of the packaging container; and,

FIG. 9 is an enlarged partial view showing a portion of the packaging container marked 9 in FIG. 1.

The dash-dash broken lines illustrate portions of the packaging container that form no part of the claimed design. The dot-dash broken lines represent enlarged partial views and form no part of the claim.
